US00D976386S

(12) **United States Design Patent** (10) **Patent No.:** **US D976,386 S**
(45) **Date of Patent:** **** Jan. 24, 2023**

(54) **EARPLUG**

(71) Applicant: **Haipa Techlife (Shenzhen) Co., Ltd.**,
Shenzhen (CN)

(72) Inventor: **ZhaoTang Zhang**, Shenzhen (CN)

(73) Assignee: **Haipa Techlife (Shenzhen) Co., Ltd.**,
Shenzhen (CN)

(**) Term: **15 Years**

(21) Appl. No.: **29/783,788**

(22) Filed: **May 14, 2021**

(51) **LOC (14) Cl.** **24-04**

(52) **U.S. Cl.**

USPC **D24/106**

(58) **Field of Classification Search**

USPC D24/106, 173, 174, 175; D14/223;

D29/112

CPC A61F 11/08; A61F 11/12; A61F 11/085;

H04R 1/1016
